UNITED STATES PATENT OFFICE.

WILLIAM A. LAVERTY, OF PHILADELPHIA, PENNSYLVANIA.

SUSPENDERS.

SPECIFICATION forming part of Letters Patent No. 276,834, dated May 1, 1883.

Application filed March 16, 1883. (No model.)

To all whom it may concern:

Be it known that I, WILLIAM A. LAVERTY, a citizen of the United States, and a resident of Philadelphia, Pennsylvania, have invented 5 certain Improvements in Suspenders, of which the following is a specification.

The object of my invention is to prevent the rapid wearing out of the strips of leather or fabric whereby the webs of suspenders are 10 secured to the usual metal rings or loops interposed between the shoulder straps and the waist-straps; and this object I attain in the manner which I will now proceed to describe, reference being had to the accompanying drawings, in which—

Figure 1 is a perspective view of sufficient of a pair of suspenders to illustrate my invention, and Fig. 2 an enlarged vertical section.

A A represent part of the shoulder-straps 20 of a pair of suspenders; B B, part of the rear waist-straps, and D the metallic loop connecting them, the upper portion of the loop being contained within the folded strip a, of leather or fabric, secured to the straps A, and the 25 lower portion of the loop being contained within a similar folded strip, a, secured to the straps B. This is an ordinary means of connecting the straps; but owing to the wear and strain of the metal loop on the strips a the latter soon become worn through or torn out, 30 and the suspenders must be discarded. In order to prevent this rapid destruction of the strips a, I employ a washer, b, of sheet metal or other material calculated to resist wear, 35 this washer being introduced between the folded strip a and the loop D, as shown in Fig. 2, so as to prevent the contact of said strip with the loop. The washers are prefer-

ably made of sheet metal bent into U form, as shown, so that they can be readily applied 40 to the loop before fitting the folded strip a thereto.

I am aware that strengthening-pieces have been applied to the outside of the strips a; but the pieces, when so applied, must be much 45 larger than the washers b which I employ, and means for securing the pieces in place must be employed, whereas the loop itself serves to retain in their proper position the washers which I use. Greater freedom of move- 50 ment of the parts is also permitted, as there is not the same amount of friction between the loop D and washer b as there would be between the loop and the leather or fabric composing the strip a.

Rings may be employed instead of the loop shown, and at the front ends of the suspenders the ring or loop may be secured to the waist-straps only in the manner shown, the upper portion of said ring or loop being adapt- 65 ed to a hook on the buckle of the shoulder-strap.

I claim as my invention—

The combination of the ring or loop D and shoulder or waist straps of a pair of suspenders, with the folded strip a and the washer b interposed between said folded strip and the ring or loop, as set forth.

In testimony whereof I have signed my name to this specification in the presence of two sub- 70 scribing witnesses.

WM. A. LAVERTY.
